G. SALTSMAN.
SPARK ARRESTER.

No. 331,089.

Patented Nov. 24, 1885.

ATTORNEY

UNITED STATES PATENT OFFICE.

GEORGE SALTSMAN, OF BLOOMINGTON, ILLINOIS.

SPARK-ARRESTER.

SPECIFICATION forming part of Letters Patent No. 331,089, dated November 24, 1885.

Application filed January 24, 1884. Serial No. 118,556. (No model.)

To all whom it may concern:

Be it known that I, GEORGE SALTSMAN, of Bloomington, in the county of McLean, and in the State of Illinois, have invented certain new and useful Improvements in Spark-Arresters and Smoke-Consumers; and I do hereby declare that the following is a full, clear, and exact description thereof, reference being had to the accompanying drawings, and to the letters of reference marked thereon, making a part of this specification, and in which—

Figure 1 is a vertical section through a smoke-stack. Fig. 2 is a vertical section at right angles to Fig. 1; Fig. 3, a horizontal section 15 through the line $x x$ of Fig. 1.

This invention relates to certain new and useful improvements in spark-arresters, having for its object the arresting of the sparks by fans operated by the rising products of combustion, heated air, and exhaust-steam passing upward through the smoke-stack, in which fans are arranged, and also utilizing a large per cent. of what are now the waste products of combustion; and to this end the invention consists in novel features of construction and combination and arrangement of parts, all as will be hereinafter fully described, and set forth in the claims hereto annexed.

In the drawings, A represents an outer cylinder or stack, which, being merely for looks or appearance, may be dispensed with, if desired, and B the inner cylinder or smoke-stack, through which the products of combustion—smoke, gases, and sparks—pass upward, and within said cylinder or smoke-stack B, project the spark-arresting fans C C, and partially revolve one above the other, and in such close proximity as the fan-blades may slightly lap each other, and thereby arrest the 35 sparks, &c., in their upward course and deliver them into the discharge-spouts connected with the usual fire-box of a boiler. The fans C C are operated by the rising products of combustion, heated air, and exhaust-steam, which are admitted through the exhaust-pipe h, near the base of the inner cylinder or smoke-stack, B, and which exhaust-pipe may extend 45 upward in said stack, as shown, and the admission of the exhaust-steam into said pipe 50 controlled by a valve or stop-cock, as may be found expedient. The fans C C are connected by beveled or frictional gearing c c with the

fans D D, (said gearing being mounted on their respective shafts,) and operate the latter fans, D D, which fans force air down 55 through the tubes G G into conduits F F, thereby creating an exhaust, which draws and forces the sparks, smoke, and other products of combustion received into said conduits F F from the spark-arresting fans C C into the 60 fire-box of the boiler. The fans C C are apt to revolve too rapidly, and getting under too great momentum the sparks are liable to go by said fans, and thus escape upward through the cylinder or stack B. This is to a great 65 extent overcome by the fans D D retarding the momentum of the fans C C. It will therefore be seen that the fans D D have a twofold function: to check somewhat the otherwise, perhaps, too rapid motion of the fans C C, and, 70 secondly, to furnish an exhaust for sparks, smoke, &c., passing into the conduits F F, and thence forced into the fire-box, furnishing a draft for the fire, which, in connection with the gases passing over the fire, assists in consuming the sparks and other products of combustion forced back in the fire-box from the 75 inner cylinder or smoke-stack, B.

d d represent small tubes communicating with the chambers of fans C C near their upper ends, as shown in plain and dotted lines, Fig. 1, through which air is forced by one of the fans D, for the purpose of cleaning the fan-chambers of smoke, soot, &c., and possibly to a slight extent retard the momentum of the 85 spark-arresting fans C C.

When the outer cylinder or stack, A, is used, the space between it and the inner cylinder or stack, B, should be closed near the top, as shown in Fig. 1, to prevent the upward passage and 90 escape of the products of combustion through said space.

Having thus fully described my invention, what I claim as new, and desire to secure by Letters Patent, is—

1. The combination, with the cylinder or smoke-stack B, of the spark-arresting fans C C, arranged one above the other and projecting into the stack, so as to slightly overlap each other, and operated by the upward or rising products of combustion, heated air, and steam through said stack B, substantially as specified.
2. The combination, with the cylinder or

smoke-stack B, and fans C C, arranged there-in, as shown, and operated by the upward or rising products of combustion, heated air, and steam through said stack, of the fans D D, 5 connected to and operated by the fans C C, and the conduits F F, and tubes G G, sub-stantially as and for the purpose herein shown and described.

3. The combination, with the cylinder or 10 smoke-stack B, of the fans C C and their chambers provided with the tube or tubes d, and the fan D, all arranged to operate sub-stantially as herein shown and described.

4. The combination, with the cylinder or

smoke-stack B, of the fans C C and their 15 chambers provided with the tubes d d, the conduits F F, fans D D, and tubes G G, all arranged to operate substantially in the man-ner as and for the purpose herein shown and described.

20

In testimony that I claim the foregoing I have hereunto set my hand this 3d day of January, 1884.

GEORGE SALTSMAN.
